UNITED STATES PATENT OFFICE

92,387

DESIGN FOR A BROILING PAN

Almer H. Brodbeck, St. Louis, Mo., assignor to
American Stove Company, St. Louis, Mo., a
corporation of New Jersey

Application April 3, 1934, Serial No. 51,307

Term of patent 14 years

To all whom it may concern:

Be it known that I, ALMER H. BRODBECK, a citizen of the United States, residing at St. Louis, and State of Missouri, have invented a new, original, and ornamental Design for Broiling Pans, of which the following is a specification, reference being had therein to the accompanying drawings.

Figure 1 is a top plan view of a broiling pan showing my new design.

Fig. 2 is a transverse sectional view of Figure 1 on the dotted line 2—2 thereof.

Fig. 3 is a bottom plan view of my new design.

Fig. 4 is a central transverse vertical section of Figure 1.

The predominant feature of this design consists in forming a pan with a central outwardly

bulged portion, a curved depression that extends into said bulged portion and also extends into the main portion of the pan and a longitudinally extending depression one end communicating with the first said depression, the longitudinally extending depression gradually tapering in width from the first said depression inwardly across the pan substantially to a point and ending at substantially the opposite side of the pan from the said first mentioned depression.

I claim:

The ornamental design for a broiling pan, as shown and described.

In testimony whereof, I hereto affix my signature.

ALMER H. BRODBECK.
